(57) **CLAIM**

The ornamental design for a laser cabinet, as shown and described.

DESCRIPTION

FIG. 1 is a top front and left side perspective view of a laser cabinet, showing our new design;

FIG. 2 is a top plan view thereof;

FIG. 3 is a front elevational view thereof;

FIG. 4 is a right side elevational view thereof, the left side being a mirror image; and,

FIG. 5 is a top, front and left side perspective view thereof on a reduced scale and in use condition.

The elements shown in broken lines throughout the drawings form a part of the claimed invention.
